(57) **CLAIM**

The ornamental design for a suspended rectilinear light fixture, as shown and described.

DESCRIPTION

FIG. 1 is a perspective view of the suspended rectilinear light fixture showing my new design;

FIG. 2 is a top plan view thereof;

FIG. 3 is a front elevational view thereof;

FIG. 4 is a right side elevational view thereof; the left side elevational view being a mirror image thereof;

FIG. 5 is a bottom plan view thereof; and,

FIG. 6 is an enlarged sectional view of FIG. 3.
